UNITED STATES PATENT OFFICE.

WILLIAM H. DAVIS, OF FEDERALSBURG, MARYLAND.

TICK-TACK.

No. 901,325.

Specification of Letters Patent.

Patented Oct. 20, 1908.

Application filed April 3, 1908. Serial No. 424,963.

To all whom it may concern:

Be it known that I, WILLIAM H. DAVIS, a citizen of the United States, residing at Federalsburg, in the county of Caroline and State of Maryland, have invented new and useful Improvements in Tick-Tacks, of which the following is a specification.

This invention relates to improvements in that species of devices known as tick-tacks and the said invention consists in the construction, combination and arrangement of devices hereinafter described and claimed.

In the accompanying drawings, Figure 1 is a perspective view of a tick-tack constructed in accordance with my invention, showing the same in use. Fig. 2 is a sectional view of the same. Fig. 3 is a detail sectional view on a plane at right angles to that of Fig. 2.

20 In accordance with my invention, I provide a handle 1 which has a pair of arms 2 at one end provided with inwardly extending bearings 3. The said handle is here shown as made of a single piece of wire 25 which is doubled and bent to form the hand hold 4 having an eye 5 at its outer end, coils 6 which connect the wire sides of the hand hold together at the point from which the arms 2 extend and the bearings 3 bent to 30 also form hooks 7.

A revoluble element 8, which is here shown as in the shape of a spool having a central drum portion 9 and circular heads 10, is disposed between the arms 2 of the handle and the ends of the bore 11 of said revoluble element or drum are engaged by the bearing hooks 7 which extend thereinto as shown in Figs. 2 and 3. The heads 10 are serrated or notched at their periphery as 40 at 12.

A spring 13, which in the practical embodiment of the invention may be a rubber band of suitable size, is disposed in the bore of the revoluble element and engaged 45 with and serves to connect the bearing hooks 7.

7. A pin 14 which extends transversely through the spool also extends through the said spring to connect the latter to the revoluble element so that when the revoluble element is turned in one direction by the unwinding of a cord 16 which it attached thereto, the said spring becomes wound and when the tension of the cord is relaxed the said spring serves to rotate the 50 revoluble element in the reverse direction.

The cord passes through the eye 6 of the handle, said eye serving as a guide element for the cord and in practice the latter is provided at its outer surface or free end with a suitable button or other stop device 60 to prevent it from slipping through said guide.

Initially the cord is maintained in a wound condition upon the drum or revoluble element by the action of the spring. In the 65 operation of the toy or tick-tack, the handle is grasped by one hand, the roughened edges of the heads of the revoluble element or drum are caused to bear against a surface, such as a pane of glass in a window and the 70 cord is then drawn out rapidly by the other hand in such manner as to cause the drum to rapidly revolve and thereby by reason of its engagement with such glass pane or other surface make the desired sound. The volume and extent of the sound may be increased or diminished by pressing the heads of the drum or revoluble element against the pane or other surface with the requisite 75 degree of force.

80 I do not desire to limit myself to the precise construction and arrangement of devices herein shown and described, as it is evident that modifications may be made therein within the scope of the appended 85 claims.

Having thus described the invention, what I claim as new and desire to secure by Letters Patent is:—

1. A toy of the class described comprising 90 a handle made of wire bent to form a hand-hold, a guide element at the inner end of said hand-hold and a pair of arms at said inner end of the hand-hold and provided with inwardly extending hooks, a drum having a bore receiving said hooks and further provided with roughened peripheral portions, a spring in said bore engaged with said hooks and connected at an intermediate portion to said drum, said spring being coiled 95 when the drum is rotated in one direction and a cord passed through the guide element of the handle, attached to said drum and wound on said drum in the required direction to cause said drum to coil said spring 100 when said cord is uncoiled or unreeled from said drum.

2. A toy of the class described comprising 105 a handle having a pair of arms provided with inwardly extending hooks, a drum hav-

ing a bore receiving said hooks and further provided with roughened peripheral portions, a spring in said bore engaged with said hooks and connected at an intermediate portion to said drum, said spring being coiled when the drum is rotated in one direction and a cord attached to said drum and wound thereon in the required direction to cause said drum to coil said spring when

10 said cord is uncoiled or unreeled from said drum.

In testimony whereof I affix my signature in presence of two witnesses.

WILLIAM H. DAVIS.
